WHEEL COVER

Sture Lennart Asberg, Partille, Sweden, assignor to
SKF Nova AB, Goteborg, Sweden

Filed June 20, 1973, Ser. No. 371,580

Claims priority, application Sweden Dec. 18, 1972

Term of patent 14 years

Int. Cl. D12—16

U.S. Cl. D12—206

FIG. I.

FIG.2.

FIG.3.

FIG.4.

FIG. 5.

FIG. 6.

FIG. 1 is a perspective view of a wheel cover showing my new design;

FIG. 2 is a front elevational view thereof;

FIG. 3 is a sectional view taken on line 3-3 of FIG. 2;

FIG. 4 is a perspective view of a wheel cover showing a second embodiment of my new design;

FIG. 5 is a front elevational view thereof; and

FIG. 6 is a sectional view taken on line 6-6 of FIG. 5.

The broken lines in the drawing are for illustrative purposes only.

I claim:

The ornamental design for a wheel cover, substantially as shown and described.
